MULTIWAVE VARIABLE RESONATOR

Lewis D. Eckard, Washington, D. C.

Application January 10, 1939, Serial No. 250,238

6 Claims. (Cl. 171—119)

The present invention relates to the combination of a new and useful multi-coil transformer with a single tuning condenser to provide a multi-wave variable resonator.

It is customary in the manufacture of all wave radio sets today to utilize three or four small coils. There are usually four antenna coils, four inter-stage or R. F. coils and four oscillator coils in the radio circuit. These all wave sets are equipped with the standard 350 mmmfd. tuning condensers and suitable padding and trimming condensers with a capacity of 15 to 30 mmmfd. The use of small padding and trimming condensers to align the circuits in the radio set, or bring the various coils in each stage of tuning into a resonant condition, prevents the utilization of the minimum capacity of the tuning condenser. This results from the fact that no matter what capacity range the tuning condenser has the 15 mmmfd. or 30 mmmfd. padding condenser always must be taken into account.

Another object is to provide a radio set which has only one inductance coil per stage of tuning.

Another object is to provide an inductance coil for a radio set, either a transmitter or a receiver, which is adapted to expand or contract to vary the inductance.

Another object is to eliminate the padding or trimming condensers now used in all wave sets to align the circuits or bring about a resonant condition.

A further object is to provide an electrical circuit arrangement which utilizes the minimum capacity range of the tuning condenser.

Another object is to provide a radio set which gets greater wave band coverage per unit coil.

Still another object is to utilize in combination with the electrical circuit of a radio, a coil which has the most efficient ratio of diameter of coil to winding length of wire thereon.

Another object is to provide a more simplified and less expensive switching arrangement in an all wave radio set.

Another object is to provide a more simplified and less expensive wiring system for an all wave radio set.

Another object is to eliminate the paralleling and close proximity of the radio frequency wires to the switching apparatus.

Other and further objects and advantages of the invention will be apparent from the following detailed description and as more particularly pointed out in the claims.

In the drawings forming part of this applica-

tion, like numerals of reference indicate similar parts in the several views and wherein:

Figure 1 is an elevation of one of the inductance coils, partly in section, in expanded form and embodying the principal features of the invention.

Figure 2 shows the inductance coil partly in section and in contracted form.

Figure 3 is an end view of the inductance coil, 10. Figure 4 is a diagrammatic sketch of the electrical circuit hookup when the inductance coil is expanded.

Figure 5 is a diagrammatic sketch of the electrical circuit hookup when the inductance coil is contracted, and

Figure 6 is a diagrammatic sketch showing the electrical circuit hookup of the two end strands of the inductance coil when the inductance coil is in expanded and contracted form.

Referring now to the drawings and more particularly to Figures 1 and 2, the numeral 10 indicates generally a cylindrical coil or wire carrying member of light Celluloid, hard rubber or the like. The coil 10 has been spirally cut to provide a helical portion 11 extending substantially throughout the length of the said coil 10, and which is of such a flexibility that it can expand or contract. A cable of wire 12 is disposed at one end of the coil 10 and is wound spirally upon the helical portion 11. The cable 12 is composed of wires of equal length and equal diameter, and comprises the primary windings of the coil and is shown as comprising two insulated wires of equal length and diameter and two turns on the flexible helical portion 11 of the coil 10. This invention is intended to cover any number of insulated wires in the primary windings and although it is preferred to have the wires in cable form it is not necessary.

40 A cable of wire 13 is disposed upon the helical portion 11 of the coil 10 at the other end thereof in spaced relation from the primary windings 12. These windings 13 constitute the secondary windings of the coil. As shown, the cable 13 comprises ten insulated wires of equal length and diameter and ten turns on the flexible helical portion 11 of the coil 10, but the number of wires may be changed without departing from the scope of this invention.

45 A solid, uncut portion 14 of the coil 10 is disposed outwardly of the primary windings 12 and is centrally apertured and proportioned to threadedly engage the threaded end of the spindle 15 which passes centrally through the coil 10. A nut 16 threadedly cooperates with the

threaded end of the spindle 15 to move the portion 14 one way or the other along the said spindle. The spindle 15 does not move longitudinally in this operation. This selective movement slightly changes the inductance of the coil as it moves the wire turns in cable form closer to or farther from one another, and is important in aligning up the circuits at the factory. Inasmuch as there is one coil used per stage of tuning, it is always necessary to adjust the various coils to obtain a condition of resonance. Heretofore a padding or trimming condenser was used for this purpose. After the fine adjustment has been made at the factory by suitably changing the inductance of the coil to obtain complete resonance the nut 16 may be sealed so that it may not be tampered with.

The spindle 15 is suitably anchored at the end carrying the portion 12. This is the fixed or stationary end of the coil.

The spindle 15 is anchored at the other end thereof in the member 17 and passes centrally through another solid uncut portion of hard rubber material 19 which is similar to the member 14. Mounted on the circumferential surface of the cylindrical portion 19 are a plurality of metal studs 20, 20'; 21, 21'; 22, 22'; 23, 23'; 24, 24'; 25, 25'; 26, 26'; 27, 27'; 28, 28'; 29, 29'; 31, 31'; 32, 32'.

The studs 31, 31' and 32, 32' are the contact members for the free ends of the wires in the primary circuit and are of brass or the like.

The studs 20, 20', 21, 21', etc. are the contact members for the free ends of the wires in the secondary circuit, each wire having two free ends. The free ends of the wires of both the primary and secondary windings are preferably soldered to their respective brass studs and can extend centrally through the interior of the inductance coil so as to be out of the way. The studs can be molded into the plastic coil 10 if it is desired to do so. The said studs are preferably small and recessed somewhat so that a better connection can be obtained with the contacts 34 and 35, hereinafter referred to in greater detail.

A cylindrical insulated member 33 is disposed outwardly of and around the coil 10 adjacent to the movable member 19 and extends substantially half the length of the coil. The member 33 is rigidly supported by the chassis in any suitable manner. A plurality of metallic spring bars or other conductor strips 34 are mounted on the inner surface of the member 33 spaced from the cable 13, and each conducting stop 34 contacts a pair of brass knobs or studs, e.g. 21, 20'. The studs 21, 20', 22, 21', etc., on the member 19 contact the spring strips 34 when the coil 10 is in a contracted or compressed form. This is best shown in Figure 2 when the primary windings are in series and the secondary windings are likewise in series. Figure 5 shows the electrical circuit when coil 10 is compressed.

A plurality of pairs of metallic strips or rings 35 are mounted on the inner surface of the member 33 spaced from said metallic strips 34. The studs on the member 19 contact the rings 35 when the coil 10 is in an expanded form as shown in Figure 1. The electrical hookup for this expanded coil condition is shown in the wiring sketch of Figure 4. In this position of coil 10 the primary windings are in parallel and the secondary windings are likewise in parallel.

The coil 10 has preferably a diameter of 1 1/2 inches and a length of 1 1/2 inches in its com-

pressed form, although a coil of other dimensions can be used. In its expanded form the coil has a length of approximately 3 inches.

Outwardly of the chassis is disposed a cable drum 36 which is suitably supported by the said chassis and upon which is wound a light cable 37 which extends through the said chassis and longitudinally through the coil 10 and around the pulley member 38 which is mounted on the member 14 at the relatively fixed end of the coil 10. The cable 37 after passing over the pulley 38 which is adapted to rotate extends longitudinally through the interior of coil 10 and is suitably securely fixed to the member 19, at the movable end of the coil 10. The ratio of the diameter of the drum 36 to the length of the cable 37 is preferably such that a three-quarter turn of the said drum 36 will completely expand or completely contract the coil 10 to put the members 34 or 35 in operative position.

It is to be understood that the drawings show only one coil which is adapted for one stage of tuning. As pointed out there are usually three or four stages of tuning. For example, if there were an antenna, radio frequency and an oscillator stage it would be necessary to have three coils similar to the one shown and described. These three coils will be suitably ganged together so that a turn on the drum cable 36 will simultaneously expand or compress the three coils, creating an all parallel or an all series circuit condition, as described. The three coils expand the same amount and if there is a resonant condition when they are in their compressed form that resonant condition will be maintained as they expand through exactly the same distance upon one turn of the drum 36.

In case of interstage coils the secondary circuit is in the grid ground circuit throughout, and the primary is in the plate circuit of the previous tube and B' plate potential and is adaptable to any oscillator circuit.

Figures 4 and 5 more clearly show the wire connections diagrammatically. In Figure 4 the primary windings of the coil 10 is in the antennaground circuit. In the secondary winding there is a parallel wiring condition as follows: studs 20, 21, 22, 23, 24, 25, 26, 27, 28 and 29 are connected together; studs 20', 21', 22', 23', 24', 25', 26', 27', 28' and 29' are all connected together. Stud 20 is connected to the grid G, and stud 29' is connected to the ground.

The efficiency of the coil wherein an equal number of turns of wire of equal length and equal diameter are used in parallel can best be shown by an example.

On the basis of a hundred turns of wire on four coils each having a diameter of 1 1/8 inches and a length of 1 1/2 inches, note the following:

	Inductance, microhenrys
1st coil, 10 turns	6.8
2nd coil, 20 turns	27.0
3rd coil, 30 turns	61.0
4th coil, 40 turns	110.0

Applying the formula

$$\frac{1}{L} = \frac{1}{L_1} + \frac{1}{L_2} + \frac{1}{L_3} + \frac{1}{L_4}$$

we have L equaling 5 microhenrys.

If ten coils are used each having the same number of wire turns, as in the present invention and using wire of equal length and equal diameter, L is found to be 2.6 microhenrys.

This computation does not take into account additional losses due to the unbalanced resistance of the various coils having an unequal number of wire turns. Where all the coils have the same number of wire turns this additional loss is avoided as the current will divide itself equally through the various coils.

In Figure 4, the numeral 40 indicates a variable tuning condenser which is preferably in parallel with the grid ground circuit. The expansion of the coil 10 puts the primary windings 12 in parallel and the secondary windings 13 in parallel to change the inductance of the said coil and to alter the capacity-inductance relation in the circuit and permits short wave reception or transmission, since the inductance is low.

In other words, when the coil 10 is expanded the radio set receives high frequency waves.

In Figure 5 the wires of the primary winding 12 are shown in series with one another and the secondary windings are in series with each other. In this series relation the following wiring connections would result in the secondary windings: 20 would be connected to the grid G, 20' to 20, 21' to 22, 22' to 23, 23' to 24, 24' to 25, 25' to 26, 26' to 27, 27' to 28, 28' to 29, and 29' to ground. When the primary windings of the coil are in series and the secondary windings are in series the set receives long radio waves as the inductance is high and there is a corresponding inductance-capacity change in the circuit.

In Figure 6, the strands of wire have been designated generally with the same numeral as the studs to which they are connected. In the contracted position of the inductance coil the top end of strand 28 is connected to stud 20 and top end of strand 29 is connected to stud 29. The lower end of strand 28 is connected to stud 20' and the lower end of strand 29 is connected to stud 29'. Contact 34 closes the circuit 20'-29 thus placing these windings in series. Contacts 39 are insulated from each other and are each connected to one of the rings 35 and these in turn are connected to the outside circuit, i. e., the condenser, grid and ground.

In the expanded position of the inductance coil the studs 20 and 29 are paralleled by being connected to ring 35 (top) while studs 20' and 29' are paralleled by being connected to (bottom) ring 35.

It is to be understood that in Figure 6 only two strands of wire have been shown to illustrate the electrical connections and that any number of strands may be used. The strands of wire should be of sufficient length to permit the full travel of the inductance coil from its contracted to its expanded position.

After the various inductance coils have been aligned in the factory by the selective operation of the nuts 16 to obtain resonance and the nuts 16 have been suitably sealed one would operate the all wave set covered by this invention as follows: if the broadcast band was desired the inductance coils would be compressed, Fig. 2: if the short wave band is desired, the cable drum 36 is rotated approximately three quarters of a turn to a point where a suitable lug (not shown) stops its motion. The coils are now expanded and the inductance thereof is considerably reduced. The coil 10 is kept in alignment by the spindle 15 which passes through the end of the member 18.

There will be obvious changes in this invention, e. g., the inductance coils will be shielded

in the usual manner to protect against stray magnetic fields or lines of force and also against the overlapping of interstage magnetic couplings. It is intended to cover such changes and the applicant desires to be limited only by the scope of the prior art and the claims appended hereto.

I claim:

1. In a tuning circuit of an all wave receiving set; an inductance coil adapted to expand or contract comprising; an expandable portion extending substantially throughout the length of said coil, primary and secondary windings disposed on said expandable portion in spaced relation, said primary windings comprising a plurality of insulated wires in coil form of equal length and diameter, said secondary windings comprising a plurality of insulated wires in coil form of equal length and diameter, a relatively non-expandable movable portion having a plurality of spaced contact members on the surface thereof and disposed at one end of said coil, two series each comprising a plurality of spaced apart contact members and each cooperating with said first mentioned contact members, each of said first mentioned contact members being connected to a free end of one of the insulated wires in said primary and secondary windings, means responsive to contraction of said windings to interconnect the wires therein in series, means responsive to expansion of said windings to interconnect the wires therein in parallel and manually operated means to expand or contract the said inductance coil.

2. In a tuning circuit of an all wave receiving set; an inductance coil adapted to expand or contract comprising; an expandable portion extending substantially throughout the length of said coil, primary and secondary windings disposed on said expandable portion in spaced relation, said primary windings comprising a plurality of insulated wires in coil form of equal length and diameter, said secondary windings comprising a plurality of insulated wires in coil form of equal length and diameter, a relatively non-expandable movable portion having a plurality of pairs of spaced contact members on the surface thereof and disposed at one end of the said coil, two series each comprising a plurality of spaced apart contact members and each cooperating with said first mentioned contact members, each pair of said first mentioned contact members being connected one to one free end of the other to the other free end of one said insulated wires, means responsive to contraction of said windings to interconnect the wires therein in series, means responsive to expansion of said windings to interconnect the wires therein in parallel, and manually operated means to expand or contract the said inductance coil.

3. In a tuning circuit of an all wave radio receiving set having antenna-ground and grid-ground circuits, an inductance coil adapted to expand or contract comprising; an expandable portion extending substantially throughout the length of said coil, primary and secondary windings disposed on said expandable portion in spaced relation, said primary windings comprising a plurality of insulated wires in coil form of equal length and diameter and in series with the antenna-ground circuit, said secondary windings comprising a plurality of insulated wires in coil form of equal length and diameter, and being in the grid-ground circuit, a relatively non-expandable movable portion having a plurality of

pairs of spaced contact members on the surface thereof and disposed at one end of the said coil, two series each comprising a plurality of spaced apart contact members and each cooperating with said first mentioned contact members, each pair of said first mentioned contact members being connected one to one free end the other to the other free end of one of said insulated wires, means responsive to contraction of said windings to interconnect the wires therein in series, means responsive to expansion of said windings to interconnect the wires therein in parallel, and manually operated means to expand or contract the said inductance coil.

4. An inductance coil adapted to expand or contract a predetermined distance comprising; said coil being wound on a form having an expandible portion, primary and secondary windings disposed on said expandible portion in spaced relation and co-axial alignment, said form having a relatively non-expandible movable portion disposed at one end of said coil, said movable portion having a plurality of contact members on the surface thereof, second contact means associated with said first mentioned contact members, and manually operated means to selectively expand or contract said coil to change the cooperation between said contact members

in such manner that the interconnections between said wire are changed.

5. An inductance coil adapted to expand or contract a predetermined distance comprising; said coil being wound on a form having an expandible helical wire carrying member, primary and secondary windings disposed on said wire carrying member in spaced relation, said primary and secondary windings each comprising a plurality of insulated wires of equal length and diameter, said form having a cylindrical movable portion disposed at one end of the said coil, said movable portion having a plurality of contact members on the surface thereof, second contact means associated with said first mentioned contact members, and manually operated means to selectively expand or contract said coil to change the cooperation between said contact members in such manner that the interconnections between said wires are changed.

6. An inductance coil comprising a plurality of strands of wires insulated from one another, said strands being helically wound on a common expandible form, and means responsive to expansion and contraction of said form to control the connections between said wires.

LEWIS D. ECKARD.
